UNITED STATES PATENT OFFICE.

HOWARD G. MACDONALD, OF PITTSBURGH, PENNSYLVANIA, ASSIGNOR TO WESTINGHOUSE ELECTRIC & MANUFACTURING COMPANY, A CORPORATION OF PENNSYLVANIA.

CIRCUIT-INTERRUPTER.

1,119,971.

Specification of Letters Patent.

Patented Dec. 8, 1914.

Application filed June 8, 1907. Serial No. 377,857.

To all whom it may concern:

Be it known that I, HOWARD G. MACDONALD, a citizen of the United States, and a resident of Pittsburgh, in the county of Allegheny and State of Pennsylvania, have invented a new and useful Improvement in Circuit-Interrupters, of which the following is a specification.

My invention relates to circuit interrupters and has special reference to inclosed circuit breakers which are adapted to automatically interrupt electric circuits under overload conditions.

The object of my invention is to provide, in a device of the class above indicated, simple and conveniently disposed means for suspending the action of the overload release mechanism.

Switching devices which are arranged to automatically interrupt electric circuits under predetermined conditions are often employed for controlling the supply of energy for electric motors and other translating devices. It is a well known fact that translating devices of this character may be materially overloaded for a short period of time when their terminals are first connected to the line without any serious injury, while the same load, if applied for any considerable length of time after the device has been in operation, may bring about disastrous results.

According to my present invention, I provide a manually operated device by which an attendant may prevent unnecessary interruption of the circuit just after it has been completed. In this way, the overload release mechanism may be sensitively adjusted for the protection of the translating device under normal conditions.

Figure 1, of the accompanying drawings, is a view, partially in section, but mainly in elevation, of a circuit interrupter constructed in accordance with my invention. Fig. 2 is a plan view of the device shown in Fig. 1, and Fig. 3 is a detail view of a portion of the mechanism.

Referring to the drawings, the device here illustrated comprises a frame or body 1 which forms a casing for the operating mechanism 2, an insulating slab or plate 3, stationary and movable contact members 4 and 5, and an inclosing casing 6 for the contact members, in which a suitable insulating fluid may be disposed.

The stationary contact members 4 are secured directly to terminals 6, and the movable contact members 5 are connected to terminals 7, by means of flexible ribbons or cables 8. The movable members are mechanically connected and electrically separated by means of an insulating bar or strip 9 and may be moved into and out of engagement with the stationary contact members by means of an operating lever 10 to which the bar 9 is connected by means of the rod 11. In order that an excellent electrical contact may be obtained between the stationary and movable contact members, each of the latter comprises a cylindrical head or block 13, a screw-threaded shank 14, which passes loosely through a hole in the bar 9 and is connected to the flexible strip 8, and a helical spring 12 which is interposed between the bar 9 and the cylindrical head 13.

The operating lever 10, which is a part of the operating mechanism 2, is in the form of a bell-crank and is pivotally mounted on a stationary shaft 15. A bell-crank lever 16, having relatively short bifurcated arms 17 and 18, is keyed to a shaft 19 that is rotatably mounted so that its center line is substantially parallel to the center line of the shaft 15. The shafts 15 and 19 are supported by a portion of the casing 1, the walls of which are relatively near together at this point and form a relatively small compartment 20 which communicates with a larger compartment 21 containing the terminals 6 and 7. One end of the shaft 19 projects materially beyond the wall of the compartment 20, and an operating handle lever 22 is affixed to this shaft extension. The arm 18 of the bell-crank lever 16 is connected to an arm 23 of the lever 10 by means of a link 24. A toggle connection is thus formed and the arrangement of parts is such that a predetermined rotation of the handle lever 22 effects engagement of the stationary and movable contact members.

The weight of the movable contact members and their connecting bar is sufficient to separate these members from the stationary members and, consequently, a latch mechanism 25 is provided for holding the switch closed. The latch mechanism 25 comprises a relatively light bell-crank lever 26, which is affixed to a shaft 27, and is provided with a hook or latch 28 and a forked trigger 29. The latch 28 is pivotally at-

- tached to a projection 31 of the lever 26 by means of a pin 30 and is limited in its motion in one direction by an angle projection 32 which engages the body of the lever.
- 5 A predetermined relation is normally maintained between the lever 26 and the latch 28 by means of a tension spring 33 that is interposed between the projection 32 and the lever. The bifurcated projection 17 on the
- 10 bell-crank lever 16 supports a pin 34 which may be engaged by the latch 28 when the switch is closed.

In order that the switch may be automatically opened under overload conditions, electro-magnets 35 and 36 are connected in series with the circuits completed through the switch in a well-known manner and comprise stationary core members 37, movable core members 38 and magnet windings 39.

20 The movable core members 38 comprise magnetizable blocks that are attached to one end of hammer rods 40 which pass loosely through holes in the stationary member and which are adapted to strike the two parts of the lever arm 29 when the electro-magnets are energized. When the magnets are deenergized, the air gaps between the stationary and movable core members are determined by the position of a calibrating device 41 which comprises a cross arm 42 having forked extremities 42^a and pivotally mounted at the end of a calibrating lever 43. This calibrating lever is made up of two parts 45 and 46, both of which are affixed to 35 a shaft 44 that is rotatably mounted in a manner similar to that of the shafts 15 and 19. The part 46 may be secured in any convenient position by means of a thumbscrew 46^a, by which its outer extremity is clamped

40 to a stationary plate 47. The upper extremities of the hammer rods are provided with enlargements which engage the forked extremities of the cross arm through which the hammer rods project.

45 One end of the shaft 27 extends through the wall of the compartment 20 and a secondary handle lever 27^a is attached to this extremity. The latch 28 is normally held in engagement with the pin 34 by reason of

50 a spring 48 which is interposed between a stationary projection 49 on the wall of the casing and a relatively short arm 50 which projects from the lever 26.

The operation of the device is as follows: Assuming that the switch is connected in the circuit of an electric motor and occupies its open circuit position, if the handle lever 22 is rotated so as to close the switch and complete the motor circuit, the first rush of current will usually be sufficient to actuate the tripping magnets. When these magnets are

actuated, the hammer rods 40 will strike the arms of the bell-crank lever 26 and will move latch 28 out of engagement with the pin 34. As soon as the bell-crank lever 16 65 is released, the movable contact members 5 will move out of engagement with the stationary contact members 4, thereby interrupting the circuit which was completed through the switch.

70 When an electric motor or other translating device has been standing idle so that its windings and magnetizable core members are cold, it will, of course, carry a considerable overload for a short time without injury. In order that the tripping mechanism of my switching device may be calibrated to protect the motor under operating conditions, without being actuated by the first rush of current when the switch is first closed, the bell-crank lever 26 may be prevented from rotating by the attendant who closes the switch. The auxiliary handle lever 27^a is provided for this purpose, and it may also be employed for manually tripping the circuit breaker when it is desired to interrupt the circuit. Under normal conditions, if the current traversing the circuit which is completed through the switch surges above the value at which the tripping device is actuated, for a very short interval of time, an interruption of the circuit may be prevented by dash-pots 51 which comprise cylinders 52 and plungers 53 that are attached to the movable core members 38 of 95 the electro-magnets 36.

I desire that variations in size and arrangement of details shall be included within the scope of my invention.

I claim as my invention:

10 In a circuit-breaker, the combination with stationary and movable contact members, and closing mechanism therefor comprising an operating lever, a handle lever and a toggle link interposed between the two levers, of a latch mechanism comprising a bell-crank lever, a resiliently mounted latch constituting one arm and a two-part trigger constituting the other, an automatic release mechanism comprising stationary and movable core members for the magnet winding, a hammer-rod connected to the movable core member for actuating the trigger, and a handle lever for mechanically preventing automatic release of the latch mechanism.

11 In testimony whereof, I have hereunto subscribed my name this 31st day of May, 1907.

HOWARD G. MACDONALD.
